UNITED STATES PATENT OFFICE.

GUY F. JONTZ, OF MOLINE, ILLINOIS.

PRESSURE-GENERATOR.

1,249,767.

Specification of Letters Patent. Patented Dec. 11, 1917.

Application filed January 19, 1917. Serial No. 143,243.

To all whom it may concern:

Be it known that I, GUY F. JONTZ, a citizen of the United States, and a resident of Moline, Rock Island county, and State of Illinois, have invented certain new and useful Improvements in Pressure-Generators, of which the following is declared to be a full, clear, and exact description.

This invention relates to pressure generators, and its primary object is to provide an apparatus whereby a combustible gaseous mixture may be compressed and exploded while under compression, the exploded mixture stored in a reservoir and mixed with a jet of water or steam, whereby a hot, powerful charge is obtained which may be used for driving slide valve engines or turbine engines, tools or other machines. Another object is to provide such an apparatus with a vacuum jacket around the reservoir, whereby the heat obtained during explosion may be effectively retained. With these and other objects and advantages in view, this invention consists in the several novel features hereinafter fully set forth and claimed.

The invention is clearly illustrated in the accompanying drawings, in which:

Figure 1, is a diagrammatic view of an apparatus showing, in side elevation, a pressure generator embodying a simple form of the present invention; in side elevation, a vacuum pump, and in end elevation, a turbine engine which is driven by the generator; Fig. 2, is a detail vertical section taken on the line 2—2 of Fig. 1; and Fig. 3, is a vertical, longitudinal section through the pressure generator.

Briefly stated, the pressure generator comprises a combustion chamber in which a gaseous mixture is compressed by means of one or more pistons, and the combustible mixture ignited at the moment of highest compression—that is to say, when the cranks are on dead center; a reservoir into which the ignited combustible mixture is forced, and if desired a vacuum jacket surrounding the reservoir, and means for maintaining a partial vacuum in said jacket, and a steam or water jetting nozzle which discharges into the reservoir.

Referring more specifically to the drawings, the reference numeral 5, designates the generator as a whole, 6, a turbine engine, which for the purpose of illustration has been shown on a very small scale, and 7 a simple vacuum pump.

The generator has a cylinder 8, which is mounted upon a suitable base or crank case 9, and reciprocating in said cylinder 8, is a piston 10, which for convenience I shall term a "short stroke" piston, and reciprocating in said short stroke piston is a second piston 11, which for convenience I shall term a "long stroke" piston. Projecting out through slots 12, in the cylinder 8, are two oppositely disposed gudgeons 13, upon which are secured two connecting rods 14, the lower ends of which are secured to cranks 15, provided upon a crank shaft 16, journaled in the crank case 9. A connecting rod 17, is connected to the long stroke piston 11, by a wrist pin 18, journaled in hollow bosses 19, formed upon the inner face of the piston 11, and said connecting rod 17, is secured at its lower end upon a crank 20, that is provided upon the crank shaft 16. It will be observed from Fig. 3, that the throw of the crank 20, is much greater than the throw of the cranks 15; consequently the stroke of the piston 11, is correspondingly greater than the stroke of the piston 10. Fig. 3, shows the pistons in full lines at the point where the long stroke piston has reached the lower limit of its travel, and the short piston 10, has reached the upper limit of its travel; that is, at the end of the intake stroke and beginning of the compression stroke; said figure also shows the pistons at the very opposite ends of their limits of travel, namely, at the end of the compression stroke and beginning of the intake stroke. The short stroke piston has a port in its head 22, which is closed by a check valve 21, which opens outward from the piston, and the head 35, of the long stroke piston 11, is formed with a depressed portion 23, which receives the stem of the check valve 21, whenever the pistons reach the position shown in the dotted lines in Fig. 3. This arrangement is merely for the purpose of permitting the heads of the pistons to come close to each other when in the position shown in the dotted lines.

The cylinder head 24, of the cylinder 8, is secured to the cylinder in any desirable manner and it has a port 25, therethrough, which is closed by a check valve 26, which is held upon its seat by a spring 27 interposed between a collar 28, on the valve stem 29, and a bracket 30. The tension of the spring 27, should be sufficient to prevent the lifting of the valve 26, during the compres-

sion strokes of the pistons. Said port 25, opens to a reservoir 31, which may be secured to the cylinder head, and said reservoir 31, may be provided with a vacuum jacket 32, whereby the chamber of the reservoir 31, may be isolated from the outer atmosphere. A pipe 33, connects the vacuum jacket with the vacuum cylinder end of the pump 7, and said pump may be driven by any suitable means, although it may be connected to the reservoir 31, by a pipe 34, and may be driven by the compressed gases stored in the reservoir. A nozzle 51, connected with a source of water or steam supply opens to and discharges into the reservoir, and the hot gases therein superheat the steam, whereby the pressure in the reservoir is increased.

In the operation of the generator, the combustible charge is compressed in the space 20 between the cylinder head 24, and the top of the piston head 35, when the latter reaches the position shown in dotted lines in Fig. 3, and said part of the cylinder I shall designate as the combustion chamber 36. A spark plug 37, is shown as secured in the cylinder head, and it is arranged to ignite the compressed charge in the combustion end of the cylinder. Any suitable ignition means may be provided for operating the spark plug, and for the purpose of illustration, I have shown a disk 38, upon the crank shaft, which disk has a contact piece arranged to contact with a contact member 39, once during each rotation of the shaft. The ordinary battery system may be employed for creating the spark in the spark plug. Obviously any of the well known ignition systems, suitable for this purpose, 35 may be employed for operating the spark plug.

A gaseous mixture is supplied to the generator by a pipe 40, which communicates with a carbureter 41, of any suitable construction, and said pipe 40, communicates with the interior of the short stroke cylinder through a port 42, (see Fig. 2) in the cylinder wall 8, and a port 43, in the short stroke cylinder. Conveniently a check valve 44, opening toward the cylinder may be employed in the pipe 40.

The generator may be employed for driving slide valve engines, turbine engines, tools or other machines, and the turbine engine, 55 or other driven machines shown at 6, may be connected to the reservoir 31, by a pipe 45. A safety valve 46, is preferably interposed in the pipe 45, to prevent the pressure in the reservoir from becoming too great. The crank shaft of the generator 60 the crank shaft and a shaft of the turbine engine, and for convenience I have shown the crank shaft and a shaft of the turbine engine connected by a belt 47, trained over pulleys 48, 49.

In starting the pressure generator, the crank shaft is first driven by suitable means until sufficient pressure is developed in the reservoir to drive the slide valve engine or turbine engine.

In the operation of the pressure generator, the crank shaft 16, is driven by the turbine 6, or other driving means, and during each cycle of rotation of said crank shaft, the short stroke piston is moved to 70 the upper limit of its stroke, and the long stroke piston is moved to the lower limit of its stroke; (see dotted lines in Fig. 3) this is the suction or intake stroke of the pistons, and a gaseous, combustible mixture 75 is taken through the carbureter and into the intake chamber between the piston. Up to this time, the crank shaft has been rotated through an arc of one hundred and eighty degrees; during the rotation of said shaft 80 through the remaining one hundred and eighty degrees of rotation to complete a cycle of operation, the short stroke piston is moved from its upper position to the lower limit of its stroke, the inlet port thereby 85 covered, and the long stroke piston is moved to the upper limit of its stroke; the gaseous mixture is thereby forced out past the check valve 21, in the short stroke piston, and is forced into the compression chamber 36, 90 directly above the short stroke piston head where it is ignited by the spark plug at the instant the cranks are on dead center. The result is that the hot, exploding charge is forced past the check valve 26, in the head 95 24, of the cylinder 8, and is forced into the reservoir 31, where it mixes with the jet of water or steam coming in through the nozzle 51, thus raising the pressure. When sufficient pressure has been generated in the 100 reservoir to drive the turbine engine or slide valve engine, the valve in the feed pipe is opened. Thereafter the turbine or slide valve engine drives the pressure generator. It is to be understood that the vacuum pump 105 7, is operated to maintain a partial vacuum in the vacuum jacket 32, thereby isolating the chamber of the reservoir from the outer atmosphere to prevent extravagant dissipation of heat developed in the storage tank 110 or reservoir 31.

From the above, it is readily apparent that a high pressure of hot gases may be developed in the reservoir; that the heat developed in said gases is prevented from 115 rapid dissipation by the vacuum jacket and that increased pressure is obtained with the steam or water jet.

It is also to be understood that various changes and modifications of the exact construction is possible, without departing from the spirit of this invention. I desire, therefore, not to limit myself to the simple form of construction and arrangement of the parts shown and described, but intend in the 120 125 130

following claims to point out all of the invention disclosed herein.

I claim as new and desire to secure by Letters Patent:

5 1. In a pressure generator, a combustion chamber, means for compressing a gaseous mixture therein, comprising one piston reciprocating in said chamber, there being a valve controlled port between one side of said piston and said chamber, and a second piston reciprocating in the said first mentioned piston for compressing the charge into the said combustion chamber, means for igniting the compressed gaseous mixture, and a reservoir for receiving the ignited mixture, communicating with said combustion chamber.

2. In a pressure generator, a combustion chamber, two pistons, one within the other, and moving in opposite directions for compressing a gaseous mixture therein, means for igniting the mixture, and a reservoir for receiving the ignited mixture, communicating with said combustion chamber.

25 3. In a pressure generator, a combustion chamber, a short stroke piston reciprocating therein, and having a valve controlled passage leading to said combustion chamber, a long stroke piston reciprocating in and co-operating with the first named piston to compress a charge in said combustion chamber, piston reciprocating means, charge igniting means, and a reservoir communicating with said combustion chamber for receiving the ignited charge.

4. In a pressure generator, a cylinder having a combustion chamber at one end, two oppositely moving pistons in said cylinder for compressing a gaseous charge into the combustion chamber, piston reciprocating means, ignition means for igniting the compressed charge and a reservoir communicating with said combustion chamber for receiving the ignited charge.

45 5. In a pressure generator, a cylinder having a combustion chamber at one end, a short stroke piston and a long stroke piston reciprocating in said cylinder and arranged to force a compressed gaseous charge into the combustion chamber, ignition means, and a reservoir communicating with said combustion chamber for receiving the ignited charge.

55 6. In a pressure generator, a cylinder having a combustion chamber, a short stroke piston reciprocating in said cylinder, and a long stroke piston reciprocating in said short stroke piston, said pistons moving in opposite directions, ignition means for igniting the compressed charge in the combus-

tion chamber, and a reservoir communicating with said combustion chamber for receiving the ignited charge.

7. In a pressure generator, a cylinder having a combustion chamber, a short stroke piston reciprocating in said cylinder, and a long stroke piston reciprocating in said short stroke piston, said pistons moving in opposite directions, ignition means for igniting the compressed charge in the combustion chamber, a reservoir communicating with said combustion chamber for receiving the ignited charge, and a steam jetting nozzle arranged to discharge into said reservoir.

8. A pressure generator, comprising a cylinder, a short stroke piston reciprocating therein, and having an outwardly opening check valve in its head, a long stroke piston reciprocating in said short stroke piston, said pistons moving in opposite directions, piston reciprocating means, ignition means, and a reservoir communicating with said cylinder there being a check valve between the cylinder and reservoir opening toward the reservoir.

85 9. In a pressure generator, a cylinder having a combustion chamber at one end, two pistons moving oppositely in said cylinder, for compressing a gaseous charge into the combustion chamber, one of said pistons having a check valve in its head opening away from the interior of the piston, piston reciprocating means, ignition means for igniting the compressed charge, and a reservoir communicating with said combustion chamber for receiving the ignited charge.

10. In a pressure generator, a cylinder having a combustion chamber at one end, two oppositely moving pistons in the said cylinder for compressing a gaseous charge into the combustion chamber, a crank shaft having short and long stroke cranks formed thereon, connecting rods between said cranks and pistons, ignition means for igniting the compressed charge, and a reservoir communicating with said combustion chamber for receiving the ignited charge.

105 11. In a pressure generator, a cylinder having a combustion chamber at one end, a reservoir communicating therewith, and having a check valve opening to the reservoir, two oppositely moving pistons in said cylinder for compressing a gaseous charge into the combustion chamber, one of said pistons having a check valve in its head opening toward said combustion chamber, piston reciprocating means, and means for igniting the compressed charge.

GUY F. JONTZ.
